SINK ATTACHMENT

Milton J. Rosen, New York, N. Y.

Application March 5, 1932, Serial No. 596,986
Renewed December 8, 1934

3 Claims. (Cl. 141—11)

My invention relates to sink attachments, and more particularly aims to provide an attachment removably attachable to a sink or basin or the like to aid in the cleaning or scouring of dishes, 5 pots, pans and other articles or utensils, to which end the invention broadly contemplates a removable base or rest upon which the article may be placed for such cleaning or scouring.

The usual location of drainboards upon which 10 these various articles are usually placed for cleaning is at either end of a sink. Such location is often inconvenient and the "boards" are generally polished or enameled metal or vitreous ware, and thus provide no suitable surface for scouring, 15 being susceptible to scratching and chipping, and further presenting a slippery surface when wet.

One object of my invention is to provide a base or rest which presents a surface not easily damaged and having also a slight degree of resiliency 20 whereby to assist in retaining the pots, pans or other articles or utensils against movement or slipping during the cleaning operation.

Another object of my invention is to provide an integral construction of the base and clamping member by which the device is conveniently attached to a sink or the like.

A further object is to provide a base or rest with integral clamping means adapted to fit various sizes and shapes of sinks or the like.

Yet another object is to provide a drain for said base or rest for the proper disposal of cleaning water or other liquids which might otherwise collect upon or flow over the base or rest and on 35 to the floor or the person of the user.

A still further object of my invention is to provide a base or rest with integral clamping members, such attachment being light in weight and of inherent strength to resist breakage or damage 40 in ordinary handling, and being quickly attachable to and detachable from a sink or the like.

Still another object of the invention is to produce a sink attachment which will be simple in construction, strong and durable, and which will be low in cost of manufacture so that it may be 45 economically availed of by the public.

Other objects and advantages of the invention will be hereinafter specifically pointed out, or will 50 become apparent, as the specification proceeds.

With the above indicated objects in view, the invention resides in certain novel constructions and combinations and arrangements of parts, clearly described in the following specification 55 and fully illustrated in the accompanying draw-

ing, which latter shows embodiments of the invention as at present preferred.

In said drawing:

Figure 1 is a perspective view of the attachment as seen from the rear of a sink;

Figure 2 is a view similar to Figure 1, as seen from the front; and

Figure 3 is a vertical sectional view taken on the line 3—3 of Figure 2.

In the preferred form of my invention, the attachment includes a substantially rectangular abutment member, here shown as a molded base 10 of rubber or other resilient material, which is provided with a semi-circular or concave recess 11 extending longitudinally thereof on its lower 15 surface, and adapted to engage the front edge or rim of a sink 11'.

A clamp 12 is secured in the base 10 during the molding process, and thus becomes an integral part of the attachment.

This clamp 12 is formed of one piece of metal rod of circular cross section, bent to comprise two substantially U shaped members 13 and 14, the former adapted to engage the inner front vertical surface of a sink and the latter similarly 25 adapted to engage the corresponding outer surface of the sink. A horizontal portion 15 of the member 14 is desirably outwardly offset at 16—16 and forms a handle permitting easy and quick 30 application and removal of the attachment.

Vertical extensions 18—18 are provided with clamping portions 17—17 which are inwardly offset slightly therefrom to accommodate the usual recessed front surface of a sink or basin. These extensions 18—18 enter the base 10 at 19, and have horizontal portions 20—20, only one of 35 which latter is shown (see Fig. 3), which secure the clamp 12 in the base and prevent its withdrawal therefrom.

Downward vertical extensions 21—21 have 40 horizontal portions 22—22 terminating at the mid-point of the U shaped member 13, said horizontal portions being adapted to clamp, along their length, the inner surface of a sink or basin.

The downward vertical extensions 18—18 and 45 21—21, joined by the integral horizontal portions 20—20 at opposite sides of the base 10, form inverted U shaped portions within the base, whereby the U shaped members 13 and 14 are 50 firmly secured within the base 10; and the U shaped members 13 and 14 provide a broad-bearing clamping support for the base 10 at the inside and outside of the sink rim upon which the device is positioned.

The base 10 in this instance comprises an up- 55

per surface 25 having corrugations or ribs 26 designed to prevent slipping of the article to be cleaned, and is further provided on three sides with a continuous rim or edge 27 forming a barrier which prevents undesired overflow of cleaning water at the front and sides of the working surface 25.

The surface 25 is also downwardly inclined from its front edge, providing an effective drain 10 for the proper disposal of said liquids toward and into the interior of the sink.

The sides 28—28 are downwardly and inwardly tapered, terminating close to the points of egress of the vertical U shaped members 13 and 14. In 15 this manner weight is reduced to a minimum and the appearance of the attachment is enhanced. The clamping members may also be provided with a covering of rubber or the like to prevent injury to the sink.

20 The device as above described, while firmly attached to the sink, is not a rigid structure, but possesses inherent flexibility, the base being of resilient material and the clamp members being so proportioned as to adapt themselves to various 25 sizes and shapes of sinks or basins.

The base or rest could likewise be constructed of some non-resilient material, such as wood or metal, and could be provided with a resilient facing on its upper surface, of rubber or other material.

30 Considerable particularities of description as to materials, part details, capacities and utilities may have been herein indulged in, but it will be understood that these statements, made with 35 reference to those now preferred of the many possible embodiments of the invention illustrated in the drawing, are not in any way to be taken as definitive or limitative of the invention. Inasmuch as many apparently widely different 40 embodiments of the invention could be made without departing from the scope thereof, it is intended that all matter contained in the above description or shown in the accompanying drawing shall be interpreted as illustrative, and not 45 in any limiting sense.

It is also to be understood that the language in the following claims is intended to cover all the generic and specific features of the invention herein described, and all statements of the 50 scope of the invention which, as a matter of language, might be said to fall therebetween.

In other words, the scope of the protection contemplated is to be taken solely from the appended claims, interpreted as broadly as is consistent with the prior art.

What I claim is:

1. An attachment for a sink and the like in-

cluding a rectangular base member of resilient material and a pair of clamping members secured thereto, the lower surface of the base member having a concave recess extending longitudinally thereof, the upper surface of the base member being non-smooth and being downwardly inclined from its front edge, a continuous rim portion extending along the front edge and the two sides of the upper surface, the clamping member being formed from a single piece of metal rod secured within the base member and bent to comprise two substantially U shaped downwardly extending members adapted to engage the inner and outer surfaces of the sink.

2. A device of the class described including a 15 base member and a pair of spring clamping members secured thereto, the lower surface of the base member having a concave recess extending longitudinally thereof, the upper surface of the base member being non-smooth, to restrain slipping, into the sink, of articles abuttingly engaging said upper surface, the clamping members formed from a piece of metal rod molded within the base member and bent to comprise an inverted U shaped portion at each side 20 of said base and two substantially U shaped downwardly extending members integral with said inverted substantially U shaped portions and adapted to engage the inner and outer surfaces of a sink, the member engaging the outer 25 surface of the sink having an inwardly offset portion to engage the sink, the horizontal portion of said member being outwardly offset to provide a handle means.

3. A cleaning accessory for combination with 35 a sink and the like, comprising an abutment member of small area relative to the width of the sink and having clamping means for detachable connection to the rim of the sink, said abutment member including a base portion constituting a rest for articles to be cleaned, said base portion having a concavity in its under side to receive the upper edge of the sink rim and a non-smooth, resilient, upper surface to restrain slipping, into the sink, of articles abuttingly engaging said upper surface, and a continuous rim portion uprising from the front and two side edges of said upper surface, said detachable clamping means including depending U shaped spring arms secured to said base portion and extending downwardly therefrom at the front and rear of the abutment member and shaped to clampingly engage the inner and outer sink rim surfaces to provide broad-bearing supports for the abutment member at the inside and outside of 40 the sink-rim.

MILTON J. ROSEN.
